[57] CLAIM

The ornamental design for a food mixer, as shown and described.

DESCRIPTION

FIG. 1 is a top, front and left side perspective view of a food mixer showing my new design;

FIG. 2 is a left side elevational view;

FIG. 3 is a front elevational view;

FIG. 4 is a right side elevational view;

FIG. 5 is a rear elevational view;

FIG. 6 is a top plan view; and

FIG. 7 is a bottom plan view thereof.

The characteristic feature of the design resides in the configuration of the side mounted mixer touch control and display panel in combination with the food mixer head as best shown in FIGS. 1-3 and 5.

FIG. 2

FIG. 3
